UNITED STATES PATENT OFFICE.

JOHN M. PARONTO, OF HOYT, KANSAS.

HAY-RAKE.

SPECIFICATION forming part of Letters Patent No. 448,926, dated March 24, 1891.

Application filed December 23, 1890. Serial No. 375,617. (No model.)

To all whom it may concern:

Be it known that I, JOHN M. PARONTO, of Hoyt, in the county of Jackson and State of Kansas, have invented certain new and useful Improvements in Hay-Rakes; and I do hereby declare the following to be a full, clear, and exact description of the invention, such as will enable others skilled in the art to which it pertains to make and use it, reference being had to the accompanying drawings, which form part of this specification.

My invention relates to an improvement in hay-rakes; and it consists in the combination and arrangement of parts, which will be fully described hereinafter.

The object of my invention is to provide a hay-rake which is furnished with two sets of rake-teeth, either one of which can be brought into play whenever so desired, and in which the parts are few, simple, and not liable to get out of order while in operation.

Figure 1 is a plan view of a hay-rake which embodies my invention. Fig. 2 is an end view of the same, the near driving-wheel being removed.

A represents two driving-wheels, and B the axle, to which the wheels are rigidly secured, so that the wheels and axle revolve together. Rigidly secured to this axle, so as to always revolve with it, is the ratchet-wheel C, of any suitable size, and with which the pawls D are made to engage for the purpose of causing the box, sleeve, or frame E applied to the axle to revolve or partially revolve for the purpose of bringing into or throwing out of action either one of the two sets of rake-teeth G. The box, frame, or sleeve is made in two parts, the inner ends of which bear against opposite sides of the ratchet-wheel, and each part consists of any suitable number of pieces, which are secured together so as to extend entirely around the axle. Each part may be constructed as here shown or in any other way that may be preferred. The inner ends of these two parts of the box, frame, or sleeve are rigidly connected together by means of the frame H, which projects beyond the box or frame at each end any desired distance, and upon which frame are mounted the two pawls D, one or both of which may be spring-actuated, and which are connected by

a connecting rod J. This rod extends from the inner end of one pawl to the outer end of the other, so that when one pawl is operated the other one will be operated at the same time. 55 This construction is used to prevent one pawl from remaining in engagement with the ratchet-wheel when the other has been operated.

Loosely connected at its rear end to the revolving box, sleeve, or frame which is applied to the axle is the tongue L, which has a loop or band M secured to its rear end, and which loop or band extends around the inner end of the longer part or portion of the frame or sleeve, and which frame or sleeve has its edges 65 cut away at this point, so as to allow it to freely revolve within the band M. By this construction the tongue is attached at the center of the machine, but in such a manner that the frame or sleeve is not interfered with. 70 This tongue is braced by the bent rod or hound N, which has its rear end formed into circles or bands, and which also extend around the sleeve or frame which freely revolves in them. This hound or rod serves as a brace for the 75 tongue and prevents any lateral movement.

Pivoted upon the tongue L is a spring-actuated lever O, which extends up within easy reach of the driver, and which has an arm P projecting horizontally from its inner side. 80 This rod serves as a stop for the revolving frame H and the sleeve to which the frame is secured, and holds one of the sets of rake-teeth in an operative position. As the frame H sweeps around, the outer end of one of the 85 pawls strikes against the arm P, and the pressure against those teeth in an operative position keeps the front end of the frame H and the outer end of the pawl attached to that end pressed toward or against the rod or arm P. 90 The pressure is sufficiently great to operate both of the pawls at the same time, and thus free them from the ratchet-wheel, and as soon as the driver forces the upper end of the lever O forward, so as to move the rod or arm P 95 from under the pawl, when the pressure against those teeth in an operative position causes the frame or sleeve and the frame H secured thereto to partially revolve. As soon as the pawl is freed from the rod or arm, the 100 springs of both pawls instantly force them in contact again with the ratchet-wheel, and the

revolution of the wheels and axle causes the ratchet-wheel to revolve the sleeve and the frame H until the other set of rake-teeth are brought into an operative position.

- 5 By the arrangement of parts here shown and described the driver has but to force forward upon the upper end of the lever O, when he can dump his load and bring another set of teeth into position. The forward draft of 10 the machine is made to revolve the frame or sleeve to which the rake-teeth are connected, and hence there is nothing left for the driver to do except to operate the lever O when he wishes to dump the load. While one of the 15 pawls is pressing against the rod or arm P both pawls are freed from the ratchet-wheel, and then this wheel revolves idly around, while the rake-teeth are gathering the hay. As soon as the lever O is operated, the pawls 20 again engage with the ratchet-wheel, and the sleeve and frame H are compelled to revolve until the other pawl strikes against the rod or arm, and then the other set of rake-teeth are in position to rake.
- 25 Having thus described my invention, I claim—

1. The combination of the driving-wheels,

the revolving axle secured to and revolving with the wheels, and a ratchet-wheel rigidly secured to the axle, with a sleeve or frame 30 placed upon the axle and provided with two sets of rake-teeth, a frame, two spring-actuated pawls mounted upon opposite ends of the frame and connected together, and an operating-lever provided with a stop for the pawls 35 to strike against, substantially as shown.

2. The combination of a revolving axle, the driving-wheels rigidly secured to the axle and causing it to revolve, a ratchet-wheel rigidly secured to the axle, a sleeve or frame applied 40 to the axle and formed into separate parts, a frame for uniting the two parts of the frame rigidly together, two spring-actuated pawls mounted upon the frame and connected together, an operating-lever provided with a 45 stop for the pawls to strike against, and two sets of rake-teeth secured to the sleeve, substantially as described.

In testimony whereof I affix my signature in presence of two witnesses.

JOHN M. PARONTO.
